LIPSTICK CONTAINER WITH SAFETY FEATURE

Donald A. Seaver, West Cheshire, Conn., assignor
to Scovill Manufacturing Company, Waterbury,
Conn., a corporation of Connecticut

Application April 18, 1947, Serial No. 742,380

8 Claims. (Cl. 206—56.)

1

This invention relates to certain new improvements in containers for holding lipstick, eyebrow pencils, and similar soft pasty cosmetics in stick form, and particularly to a type of container in which the cosmetic stick is supported in a carrier cup which is moved from an enclosed casing to expose the stick for use and then withdrawn into the casing by rotating one member of the casing relative to another member, and finally covering the casing with a full length cover cap. This type of dispenser is generally known and referred to as a swivel type of lipstick container.

One of the inherent faults of the above type of lipstick containers is that frequently in packing the container for shipment, or carrying the same around in a handbag, or idly playing with the same, the members composing the container are liable to be accidentally rotated in relation to each other with the result that the cosmetic stick is forced into contact with the inside of the cap, creating disfigurement and soiling of working parts and deforming the shaped end of the cosmetic stick, to the annoyance of the user, and to the prejudice of the purchasing public.

It is, therefore, the main object of this invention to provide a change in the construction of the orthodox swivel type lipstick containers by which the unintentional movement of a cosmetic stick in its casing is effectively prevented. This is accomplished by assembling the cover cap over the casing in such a manner that the cap will have no direct frictional engagement with the outer casing, but rather is engaged upon an extended sleeve forming a part of the operating head.

In the conventional swivel type lipstick container construction it has been the former practice to make the operating head of the device as an integral part of the inside shell. In order to accomplish the ends in view I have now designed the casing so that the operating head is not formed as an integral part of the inside shell, but rather as an independent member and has a skirt extending upwardly and surrounding the adjacent portion of the outside casing shell in a relatively loose manner. The operating head, however, is interlockably connected to the inside shell by an interconnecting insert shell rigidly connecting said operating head and inside shell together as a single operating unit. By this construction, after the cover cap is assembled into position, if there is any relative rotation between the cap and the operating head, the

entire lipstick casing as a unit will be turned within the cover cap without in any way changing the relative position of the parts comprising the casing.

With these and other objects in view, the invention consists in certain novel features of construction, combinations and arrangements of parts, as will be more fully disclosed in connection with the accompanying drawing and as set forth in the annexed claims.

In the drawing:

Fig. 1 is a vertical sectional view of a lipstick container embodying the invention and showing the cover cap in its normal assembled position.

Fig. 2 is a similar view to Fig. 1 showing a modification of the invention.

Fig. 3 is a full elevational view of the container minus the cap of the embodiment disclosed in Fig. 2, and

Fig. 4 is an enlarged fragmentary sectional view of the container adjacent the operating head showing particularly the clearance and tight fit as between the several interconnected members, and which construction is applicable to either forms of the invention.

Referring now to the drawing in which like reference numerals denote corresponding parts throughout the several views, the numeral 10 refers generally to a swivel type lipstick container comprising an outside tubular casing 11 having an inside shell 12 rotatably mounted therewithin. Disposed between the casing 11 and inside shell 12 and adapted to be retained and carried by the outside casing 11 is a spiral sleeve 13 having a helical slot 14 extending from end to end thereof. In order to assure that the spiral sleeve 13 will be locked in place in the outside casing 11, an opening 15 is provided in the intermediate part of said sleeve 13 and a lug 16 is struck inwardly from the outside casing adjacent its lower edge to engage in said opening 15.

The inside shell 12, as pointed out in the objects, instead of having the operating head attached directly thereto or formed as an integral part thereof, now consists of substantially a straight cylindrical shell throughout its length and formed with a closed base end 17. The usual form of carrier cup 18 is slidably mounted within said shell 12 and has a rivet pin 19 riveted thereto with the head 19' thereof engaging in a longitudinal slot 20 provided in the wall of said shell 12 and also in the helical slot 14 of the spiral sleeve 13. As well-known in this type of lipstick containers, by merely turning the outside casing 55 relative to the inside shell or vice versa, the car-

rier cup will be elevated and retracted within the container 10.

The manual operating means for the container is in the form of a cupped shell 21 having an enlarged beaded or knurled head portion 22 and an integral skirt 23 extending upwardly therefrom and loosely surrounding that part of the outside casing 11 adjacent its lower end (see Fig. 4). The head 22 is preferably given a triple beaded or rolled knurl effect to facilitate the gripping of the same and also to add to the ornamental appearance of the device.

In order to operate the inside shell 12 relative to the outside casing 11, it is necessary to rigidly connect the inside shell 12 to the operating head shell 21. This is accomplished by an intermediate cupped interconnecting shell 24 having a reduced lower end 25 and an enlarged upper portion 26 which is considerably longer than the reduced end. The reduced portion 25 is dimensioned interiorly so that the lower closed end of the inside shell 12 has a snug fit thereto to centralize one shell relative to the other and as a further partial means to hold these parts together. The enlarged portion 26 is provided with a relatively heavy axial straight-lined knurled surface as at 27 and this enlarged portion 26 is adapted to have a drive fit within the interior of the skirt 23 of the head shell 21, the knurled surface 27 serving to interlock the two shells 21 and 24 together and particularly to prevent relative rotation. The base 28 of the interconnecting shell 24 is initially formed with a central upwardly drifted tubular rivet element 29 (shown in dotted outline in Figs. 1 and 4) which is adapted to be inserted through an opening 30 in the base end 17 of the inside shell 12 and then formed or spun outwardly as at 31 to serve as a rivet head and secure the interconnecting shell 24 rigidly to the inside shell 12 against axial separation. By this construction it will be evident that the inside shell 12, interconnecting shell 24 and operating head shell 21 will all be secured together as one integral operating unit.

It is to be noted that, when the interconnecting shell 24 is in its completely assembled position, the upper edge of the enlarged knurled portion 26 thereof is disposed a considerable distance below the upper edge of the skirt 23 and the outside casing 11 extends downwardly into said skirt substantially that distance and possibly allow for a slight clearance between the adjacent edges of said casing 11 and said enlarged portion 26 as indicated at 35. Also it is to be noted that the spiral sleeve 13 extends downwardly into the enlarged portion 26 to a shoulder 36 connecting the reduced lower end 25 with said enlarged portion 26. (See Fig. 4.)

The container 10, when not in use, is adapted to be covered by an elongated cover cap 32 that loosely fits over the outside casing 11 and is adapted to have a frictional slip fit upon the skirt 23 of the head shell 21. The cover cap 32 is slipped over the skirt 23 up to a stop as effected by a shoulder 33 interconnecting the operating head portion 22 and the skirt 23. By this construction, if any person should accidentally turn the operating head 22 relative to the cover cap 32 when assembled, the entire container unit 10 will turn within said cover cap 32, and thus prevent the rotation of the inside shell 12 relative to the outside casing such as would cause movement of the carrier cup 18 within the container 10.

The form shown in Figs. 2 and 3 is identical in all respects to Fig. 1 except that the skirt 23a of the head shell 21a is made longer than the skirt 23 of the Fig. 1 form and extends upwardly outside of the outside tubular casing 11a substantially three-quarters of its distance leaving only the upper portion 11b of the casing exposed as shown in Fig. 3. It will be apparent that the manner in which the head shell 21a is now made readily allows for this extra extension of the skirt 23a. The reason for this long skirt is that the operating head shell 21a can be readily grasped by the operator's hand and the exposed portion 11b of the outside shell 11a turned relative thereto by the thumb and index finger of the same hand, thus making this lipstick container a convenient one-hand operated device.

While this invention has been shown and described in two forms, it will be understood that other changes and variations may be made in the specific constructions shown and described without departing from the scope of the invention as defined in the appended claims.

I claim:

1. In a holder for stick cosmetics and the like, an outer casing, an inside shell having a closed base and rotatable in said casing, a cup for carrying a cosmetic stick, cooperative means in said casing for advancing and retracting said cup coincident with the rotation of said shell relative to said casing, the improvement which consists of an operating cup-shaped head shell having a closed base end and a skirt portion extending upwardly and loosely surrounding the adjacent portion of said outer casing, an interconnecting cupped shell having a closed base end and adapted to have a forced fit into the skirt of said head shell, said inside shell, interconnecting shell, and operating head shell being nested together with their respective closed base ends in abutted relationship, means connecting the base end of said interconnecting shell to the base end of said inside shell whereby said head shell, interconnecting shell and inside shell are joined together and operate as a unit, and a closure cap having a frictional fit upon the skirt portion of said operating head.

2. In a holder for stick cosmetic and the like, an outer casing, an inside shell having a closed base end and rotatable in said casing, a cup for carrying a cosmetic stick, cooperative means in said casing for advancing and retracting said cup coincident with the rotation of said shell relative to said casing, the improvement which consists of an operating cup-shaped head shell having an enlarged head portion with a closed base end and a reduced skirt portion with a connecting shoulder therebetween, an interconnecting cupped shell having a forced drive fit into the reduced skirt portion and having its upper edge disposed a distance below the upper edge of said skirt against which edge the adjacent end of the outer casing abuts as a stop, and that part of said skirt above said interconnecting shell having free rotatable engagement about the adjacent end of said outer casing, means connecting the base end of said interconnecting shell to the closed end of said inside sleeve, and a closure cap having a frictional fit upon the skirt portion of said operating head shell.

3. A cosmetic holder as defined by claim 1 wherein the means connecting the base end of said cupped shell to the closed end of said inside sleeve consists of an opening in the base end of said inside sleeve and a tubular extension formed

up from the base of said interconnecting shell and adapted to be riveted over about the opening of said sleeve base.

4. In a holder for stick cosmetics and the like, an outer casing, an inside shell having a closed base end and rotatable in said casing, a cup for carrying a cosmetic stick, cooperative means in said casing for advancing and retracting said cup coincident with the rotation of said sleeve relative to said casing, the improvement which consists of an operating cupped-shaped head shell having an enlarged head portion and a reduced skirt portion with a connecting shoulder therebetween, an interconnecting cupped shell having a base end with a reduced section adjacent its base end, the larger part of said interconnecting shell having a forced drive fit into the skirt portion of said operating head shell, the upper edge of said interconnecting shell being disposed a distance below the upper edge of said skirt portion and said latter skirt portion being freely rotatable about the adjacent end of said casing, the closed end portion of said inside shell also having a forced drive fit into the interior of the reduced section of the interconnecting shell whereby said inside shell, interconnecting shell and operating head shell are joined as a single operating unit, and a closure cap having a frictional fit upon the skirt portion of said operating head shell.

5. A cosmetic holder as defined by claim 4 wherein the exterior surface of the large section of said interconnecting shell is provided with an axial straight-lined knurl to enhance its gripping action within said skirt portion.

6. A cosmetic holder as defined by claim 4 wherein the adjacent base ends of said inside shell and interconnecting shell are riveted together to prevent axial separation.

7. A cosmetic holder as defined by claim 4 wherein the cooperative means in said casing comprises a helical sleeve carried by the interior of said casing and which sleeve has a portion which extends beyond the lower edge of said casing and is adapted to telescopically and freely fit into the enlarged section of said interconnecting cupped shell while the adjacent edge of said casing is disposed adjacent the upper edge of said interconnecting shell.

8. A cosmetic holder as defined by claim 4 wherein the cooperative means in said casing comprises a helical sleeve carried by the interior of said casing and which sleeve has a portion which extends beyond the lower edge of said casing and is adapted to telescopically and freely fit into the enlarged section of said interconnecting cupped shell, and a lug means formed inwardly from the lower edge of said casing for interlocking engagement with an intermediate portion of said sleeve.
